TYPEWRITING MACHINE

Elmer L. Wise, Bridgeport, Conn., assignor to Underwood Elliott Fisher Company, New York, N. Y., a corporation of Delaware

Application March 18, 1941, Serial No. 383,951

9 Claims. (Cl. 197—75)

This invention relates to typewriting machines and more particularly to flat platen machines of the so-called Elliott Fisher type.

In certain machines of this type at present in commercial use, two types of different characters or case are mounted on each of certain type heads and the type head is pivotally mounted on the type lever or bar to enable the types to be brought alternatively into operating or typing position. The type heads are normally held in position on the type levers to locate the upper types in operative position. In order to shift the type heads to bring the lower types into operative position, each of the shiftable type heads is provided with an arm or trigger movably mounted thereon and a relatively fixed trip disc is mounted within the arc or partial ring in which the type heads are located when the type levers are retracted. This trip disc is arranged to be engaged by said triggers during the operating strokes of the type levers to shift the type heads. The disc is normally located out of the paths of the triggers on the type heads but is movably mounted so that it may be depressed into the paths of said triggers.

This trip disc has been employed upon machines in which the type bars are operated by power and it is to such machines that the invention particularly relates. The trip disc on these machines has been located so that it engages the triggers on the type heads at a relatively late point in the movements of the type levers to engage the type with the work sheet and, with certain adjustments of the type bar operating mechanism, the engagement occurs when the type levers are moving under momentum. The result is that the movement of the levers is retarded by the engagement with the trip disc to shift the types and the types make a relatively light impression on the work.

The principal objects of the present invention are to improve the construction and mode of operation of the trip mechanism for the type heads in machines of the above type and to produce a construction in which the above disadvantage, inherent in prior trip mechanisms, is effectively avoided.

With the above objects in view, the invention contemplates a type head trip mechanism embodying the novel and improved features and constructions hereinafter described and particularly pointed out in the claims, the advantages of which will be readily understood and appreciated by those skilled in the art.

The invention will be clearly understood from the accompanying drawings illustrating the in-

vention in its preferred form and the following detailed description of the construction therein shown.

In the drawings:

Fig. 1 is a view in vertical section taken through the type carriage of a machine embodying the invention and illustrating the type bar mechanism, the type head trip mechanism and certain associated parts.

Fig. 2 is a view similar to Fig. 1 with certain parts of the type bar mechanism omitted.

Fig. 3 is a detail plan view illustrating particularly the parts of the type head trip mechanism.

The invention is illustrated as embodied in a typewriting machine of the Elliott Fisher type such as that illustrated and described in the co-pending application of Oscar J. Sundstrand, Serial No. 114,416, filed December 5, 1936, upon which Patent No. 2,239,023, dated April 22, 1941, has been granted.

The machine comprises the usual platen frame in which is mounted for vertical movement the substantially flat platen 2. A line space frame is mounted for forward and rearward movement upon rails formed upon the side bars of the platen frame. The line space frame is provided with front and rear rails upon which is mounted for movement in letter spacing direction and return, a type carriage indicated at 4 supporting the type bar mechanisms. For a full and complete disclosure of the parts above referred to which are not shown herein, reference may be had to said Patent No. 2,239,023.

The machine is provided with a series of type bars or levers 6 each pivoted at 8 to a hanger 9 secured to a semi-circular ring 10 suspended below the deck 12 on the carriage. The type bar mechanism comprises a retracting spring 14 acting on the type lever, which operates to retract the lever and tends to retain the lever in its normal position with the type head in engagement with a semi-circular buffer ring 15. The type bar mechanism further comprises an elbow lever 16 pivoted at 18 on a hanger 19 suspended from the deck 12, a link 20 connecting the elbow lever with the lower end of the type lever, a sub-lever 22 pivoted on a bracket 24 extending upwardly from the deck, a link 26 connecting the forward end of the sub-lever with the elbow lever, an intermediate lever 28 pivoted upon a fulcrum bar 30 and connected by a link 32 with the rear end of the sub-lever 22 and a retracting spring 34 acting on the intermediate lever. The intermediate lever is operated by power to impart the type impression

strokes to the type lever. The power mechanism for operating the intermediate lever comprises a radius bar 36 pivoted at 38 on a rod supported on the cover plate 40 of the type carriage, a transmitting link 42 connecting the radius bar with the intermediate lever, a driving link 44 having its lower end pivotally connected at 46 with the radius bar, a continuously rotating fluted shaft 48 and a pawl 50 mounted on the driving link and arranged to be engaged with the fluted shaft. The driving link is acted upon by a coiled spring 52 which tends to swing the same about its pivotal connection with the radius bar to carry the pawl away from the fluted shaft, this movement being limited by an arresting plate 54, and the driving link is swung in the opposite direction to engage the pawl with the fluted shaft by means of a draft link 56 connected with the upwardly extending arm of a key lever 58 pivoted at 60, said link having a shoulder arranged to engage a pin 62 on the driving link to swing said link into position to engage the pawl with the fluted shaft. During the downward movement of the driving link to actuate the type bar, the upper end thereof is arranged to engage, at a point adjacent the end of the downward movement of the link, a contact plate 64, adjustably mounted on the supporting plate 66 for adjustment toward and from the driving link. The engagement of the driving link with the contact plate limits the swinging movement of the driving link toward the fluted shaft and causes the disengagement of the driving pawl from said shaft as said shaft continues its rotation and the type bar executes the remainder of its type-impression stroke under momentum. By the adjustment of the contact plate 64, the point in the movement of the driving link at which the driving pawl is disengaged from the fluted shaft may be adjusted to adjust the type impression.

When the type bars or levers are retracted, the type heads lie in arcuate arrangement in contact with the buffer ring 15 as shown in the patent to Foothorap, No. 1,119,149, dated December 1, 1914.

The type bar mechanism and the power operating mechanism therefor disclosed in this application, has substantially the same construction, arrangement and mode of operation as the corresponding mechanism more fully illustrated and described in said Patent No. 2,239,023, referred to above.

The present type actions are similar in certain respects to the type actions shown and described in the patent to Foothorap, No. 1,251,361, dated December 25, 1917, and contain the features of slow and easy starting movement of the type bar with the greatest leverage on said bar exerted by the power mechanism during the first part of a type impression stroke of the bar and accelerated movement of the bar as it approaches the printing point. As the type bar mechanism is started on a type impression stroke from the position shown in Fig. 1, the arc of movement of the pivotal connection between the lever 16 and the link 20 is very nearly perpendicular to the arc of movement of the pivotal connection between said link and the type bar 6 and, as the type bar descends, the paths of movement of said connections become more nearly aligned. The type bar will be started smoothly and easily with the greatest leverage exerted thereon during the first part of its movement and this leverage will diminish and the

movement of the type bar will be accelerated as it approaches the work. The type head is arranged to move in a path very nearly perpendicular to the platen adjacent the end of the type-impression stroke of the type lever.

Certain of the type bars are provided with two types which are arranged to be brought alternatively into operating position in the manner common in machines of the Elliott Fisher type. The type bar 6 is an example of such a type bar. The type head mounted on this bar, the spring for holding the head in position, and the trigger for shifting the head, have substantially the same construction, arrangement and mode of operation as the corresponding parts illustrated and described in the patent to Foothorap, No. 1,119,149, referred to above.

Upon the outer end of the type bar 6 is pivoted, on an axis 68, a type head 70 upon which are mounted the types 72 and 74 in the angular relation shown in Figs. 1 and 2. Fig. 1 shows the type head in normal position on the type bar with the type 72 in position to engage the work sheet at the end of the type impression stroke of the type bar. To place the type 74 in operating position, the type head is shifted to the position shown in Fig. 2.

The movement of the type head on the type bar in a clockwise direction (Figs. 1 and 2) is limited by the engagement of a stop face 76 on the type head with the type bar 6, and the movement of the type head in a counter-clockwise direction is limited by the engagement of a stop face 78 on the type head with said type bar. The engagement of these respective stop faces with the type bar determines the operating position respectively of the types 74 and 72. The type head is locked in the position shown in Fig. 1, by means of a leaf spring 80 secured to the type bar, the angularly turned end of which is arranged to engage behind a projection 82 on the type head. This spring, when the type head is shifted to the position shown in Fig. 2, engages the opposite side of the projection 82 on said head and tends yieldingly to hold the type head in position.

The mechanism for shifting the type head comprises a trigger 84 consisting of a lever pivoted at 85 to the type head. This trigger, when swung in a clockwise direction (Figs. 1 and 2) with relation to the type lever from the position shown in Fig. 1, first has a movement independent of the type head in which it moves the spring 80 out of locking position with relation to the type head and then shifts the type head into the position shown in Fig. 2 to locate the type 74 in operating position. When the trigger is swung in the opposite direction with relation to the type lever, the trigger will shift the type head back into the position shown in Fig. 1 with relation to the type lever. The construction of the trigger is fully shown and described in said Foothorap Patent No. 1,119,149 and need not be further disclosed herein.

The trigger is arranged to engage the buffer ring 15 when the type bar is in retracted position, the engagement of the trigger with said ring then locating the type head in position on the type bar so that the type 72 is in position to be projected into engagement with the work sheet by the swinging movement of the type bar. When the type 74 is to be engaged with the work sheet, the type head is shifted into the position shown in Fig. 2 during the work engaging movement of the type bar.

The mechanism for shifting the type head into this position comprises a strip or bar 86 of semi-ring formation in plan, the ends of which are connected by a cross bar or strip 88. This semi-ring is normally suspended above the paths of the type heads so that it is located beyond the paths followed by the triggers 84 during the type impression strokes of the type bars. The ring, however, is arranged to be depressed into the paths of the triggers 84 to shift the type heads during the type impression strokes of the type bars. In the construction shown, the semi-ring 86 is provided adjacent its ends with arms 90 and is pivotally suspended upon vertically swinging arms 92 by means of screw studs 94 passing through the arms 90 and threaded into arms 92. The supporting arms 92 are secured to a rock shaft 96 mounted at its ends in bearings on the frame of the type carriage and acted upon by a coiled spring 98 connected with an arm 100 attached to said rock shaft, this spring constantly tending to raise the supporting arms 92 and normally holding the semi-ring 86 in elevated position as shown in Fig. 1. The rock shaft is actuated to depress the ring 86 into the position shown in Fig. 2 by means of a key lever 102 pivoted on the fulcrum bar 30 and carrying a roll 104 arranged to engage a cam face 106 on an arm 108 fixed to the rock shaft. The key lever 102 is normally held in elevated position by a coiled spring 110 and its upward movement under the action of the coiled spring is limited by the engagement of the lever with a stop bar 112 on the frame of the type carriage.

It is important that the trip ring 86 be located in substantially the same relation to all of the shiftable type heads when in its lowered or operative position to obtain uniformity of action. To obtain this result, in the present construction, the trip ring is controlled so that its lowered position is substantially parallel with its upper position. The trip ring is provided adjacent its opposite ends with the additional or auxiliary arms 114 each formed with a slot 116 in which engages a screw stud 118 secured in one of the suspending arms 92. When the trip ring is elevated, the forward ends thereof and the cross strip 88 are engaged with a stop face 120 on the casing of the type carriage. The slots 116 are so formed that the studs 118 are then engaged with the upper ends of the slots to locate the trip ring in the angular position on the suspending arms 92 shown in Fig. 1. When the trip ring is depressed into the position shown in Fig. 2, the cross strip 88 is engaged with the rearwardly projecting portions of stop brackets 122 secured to the casing. The slots 116 are so formed that the studs 118 are then engaged with the lower ends of said slots. This will locate the trip ring substantially in the position shown in Fig. 2, parallel with its upper position, and the ring will then be located in substantially the same relation to all the shiftable type heads.

The trip ring, when in lowered or operative position, is located relatively close to the triggers 84 of the shiftable type heads so that it is engaged by said triggers at a very early point in the type impression strokes of the type bars while the type bar is driven by power regardless of the adjustment of the type bar operating mechanism. The action of the trip ring upon the type heads will therefore not retard the movement of the type bars and the types will make as heavy impressions as desired upon the work sheet.

In order to lock the shift key lever 102 in depressed position and thereby maintain the shift

ring 86 in operative position for a number of strokes of the type bars, a shift lock lever 124 is pivoted at 126 upon a bracket 128 fixed to the frame of the machine and is provided with a locking projection 130 which normally is located below a pin 132 secured in the key lever as shown in Fig. 1. The locking lever 124 is normally maintained yieldingly in the position shown in Fig. 1 by means of a coiled spring 134 and its pivotal movement under the action of the spring is limited by the engagement of an arm 136 on the lock lever with a contact plate 138 formed on the bracket 128. With the lock lever in this position, the engagement of the pin 132 with the projection 130 prevents the accidental depression of the shift lever. Before depressing the shift lever, the upper end of the lock lever is swung rearwardly to swing the projection 130 out of position beneath the pin 132 and the shift lever is then depressed to carry the pin below said projection 130. The lock lever is then released allowing the lever to be swung by the action of the spring 134 into locking position as shown in Fig. 2. The engagement of the pin 132 with the projection 130 then holds the shift lever and the trip ring 86 in depressed position. To release the shift lever and the trip ring, the upper end of the lock lever 124 is swung rearwardly to release the pin 132, and the shift lever and the trip ring are then moved back upwardly to their normal positions by the coiled spring 110.

It is to be understood that the invention is not limited to the particular construction and arrangement of parts of the illustrated embodiment of the invention, but that the invention may be embodied in other forms within the scope of the claims.

Having explained the nature and object of the invention and having specifically described a construction embodying the invention in its preferred form, what is claimed is:

1. A typewriting machine comprising a substantially horizontal flat platen, a type head, a type lever upon the outer end of which said type head is mounted having a retracted position substantially perpendicular to the platen and arranged to move the type head in a path substantially perpendicular to the platen adjacent the end of the type-impression stroke of said lever, mechanism through which said lever is actuated having the greatest leverage on said lever at the beginning of a type-impression stroke and arranged to impart an accelerated movement to the lever in said stroke, two types mounted on said type head, means for shiftably supporting said head on the lever to locate the types selectively in position to engage a work sheet supported on the platen during the type-impression stroke of the type lever, power operated means for actuating said mechanism to operate the type lever, contact means associated with said head and movable to shift the head, a trip device normally located above the retracted position of said head and the contact means associated therewith and arranged to be lowered into position to be directly engaged by said contact means at the beginning of the type-impression stroke of the type lever to shift the head from one position to another and means for lowering and raising said trip device.

2. A typewriting machine comprising a substantially horizontal flat platen, a type head, a type lever upon the outer end of which said type head is mounted having a retracted posi-

tion substantially perpendicular to the platen and arranged to move the type head in a path substantially perpendicular to the platen adjacent the end of the type-impression stroke of said lever, mechanism through which said lever is actuated having the greatest leverage on said lever at the beginning of a type-impression stroke and arranged to impart an accelerated movement to the lever in said stroke, two types mounted on said type head, means for shiftably supporting said head on the lever to locate the types selectively in position to engage a work sheet supported on the platen during the type-impression stroke of the type lever, power operated means for actuating said mechanism to operate the type lever, contact means associated with said head and movable to shift the head, a trip device normally located above the retracted position of said head and the contact means associated therewith and arranged to be lowered into position to be directly engaged by said contact means at the beginning of the type-impression stroke of the type lever while the type lever is operated under power to shift the head from one position to another and means for lowering and raising said trip device.

3. A typewriting machine comprising a substantially horizontal flat platen, a series of type heads, a series of type levers upon the outer ends of which the respective type heads are mounted, each lever having a retracted position substantially perpendicular to the platen and arranged to move the type head in a path substantially perpendicular to the platen adjacent the end of each type-impression stroke, connections for operating said levers from the power means constructed to exert the greatest leverage on the respective levers at the beginning of each type-impression stroke and arranged to impart accelerated movements to the levers during said strokes, two types carried by each of said heads, means for shiftably supporting each head on the corresponding lever to locate the types selectively in position to engage a work sheet supported on the platen during the type-impression stroke of the type lever, a contact device mounted on each type head and movable to shift the head, said contact devices being arranged in an arc when the type levers are in retracted positions, a trip device having arcuately arranged contact means to be engaged by said contact devices to shift the type heads from normal positions, means for supporting said trip device normally above the type heads and the contact devices thereon out of operative position and for vertical movement to lower the contact means on the same to a position immediately inside the contact devices on said heads so as to be directly engaged by said contact devices at the beginning of the operating strokes of the respective type levers and means for lowering and raising said trip devices.

4. A typewriting machine comprising a substantially horizontal flat platen, a series of type heads, a series of type levers upon the outer ends of which the respective type heads are mounted, each lever having a retracted position substantially perpendicular to the platen and arranged to move the type head in a path substantially perpendicular to the platen adjacent the end of each type-impression stroke, connections for operating said levers from the power means constructed to exert the greatest leverage on the respective levers at the beginning of each type-impression stroke and arranged to

impart accelerated movements to the levers during said strokes, two types carried by each of said heads, means for shiftably supporting each head on the corresponding lever to locate the types selectively in position to engage a work sheet supported on the platen during the type-impression stroke of the type lever, a contact device mounted on each type head and movable to shift the head, said contact devices being arranged in an arc when the type levers are in retracted positions, a trip device having arcuately arranged contact means to be engaged by said contact devices to shift the type heads from normal positions, means for supporting said trip device normally above the type heads and the contact devices thereon out of operative position and for vertical movement to lower the contact means on the same to a position immediately inside the contact devices on said heads so as to be directly engaged by said contact devices at the beginning of the operating strokes of the respective type levers, arcuately arranged fixed contact means arranged to be engaged by said contact devices adjacent the ends of the reTRACTING strokes of the type levers to shift the type heads back to normal positions and means for lowering and raising said trip devices.

5. A typewriting machine comprising a substantially flat platen, a series of type levers, power means for operating said levers, a series of shiftable type heads mounted on the respective levers, a rock shaft, one or more arms on said rock shaft, a contact member pivotally suspended on said arms and arranged to swing with said arms during a portion of the movement of said arms and to pivot with relation to said arms during another portion of the movement of said arms, devices connected respectively with said type heads for engaging said member to shift the type heads during the operating strokes of the type levers, manually operable means for rocking said shaft to move said contact member into operative position and means for holding said contact member from swinging movement with said arms at one or more points in the movements of said arms to cause a relative pivotal movement of said member.

6. A typewriting machine comprising a substantially flat platen, a series of type levers, power means for operating said levers, a series of shiftable type heads mounted on the respective levers, a rock shaft, one or more arms on said rock shaft, a contact member pivotally suspended on and wholly supported by said arms and arranged to swing with said arms during a portion of the movement of said arms and to pivot with relation to said arms during another portion of the movement of said arms, contact devices connected respectively with said type heads for engaging said member to shift the type heads during the operating strokes of the type levers, manually operable means for rocking said shaft to move said contact member into operative position and stops for arresting the swinging movement of said contact member with said arms to cause the portion of said contact member adjacent the type heads to move into position to be engaged by said contact devices during the type impression strokes of the type levers.

7. A typewriting machine comprising a substantially flat platen, a series of type levers, power actuated means for operating said levers to project the types into engagement with a work sheet on the platen, a type head mounted

upon the outer end of each of said levers, two types mounted on said head, means for movably supporting said head on said lever to enable said head to be shifted into position to bring one of said types into contact with the work sheet on the platen or into position to bring the other of said types into contact with the work sheet during the type impression stroke of the type lever, contact means associated with each type head and movable to shift said head, a contact device arranged to be engaged by said contact means during the type impression stroke of each of said levers to shift the head, means for shiftably supporting said contact device comprising one or more pivoted supporting arms, means for pivotally supporting said contact device on said arms, one or more stops for holding said contact device from swinging movement with the 10 arms during a portion of the movement of said arms to cause a relative angular movement of the contact device and the arms, and means to limit the pivotal movement of the device with relation to the arms in both directions.

8. A typewriting machine comprising a substantially flat platen, a series of type levers, power actuated means for operating said levers to project the types into engagement with a work sheet on the platen, a type head mounted upon the outer end of each of said levers, two types mounted on said head, means for movably supporting said head on said lever to enable said head to be shifted into position to bring one of said types into contact with the work sheet on the platen or into position to bring the other of said types into contact with the work sheet during the type impression stroke of the type lever, contact means associated with each type 35

head and movable to shift said head, a contact device arranged to be engaged by said contact means during the type impression stroke of each of said levers to shift the head, means for shiftably supporting said contact device comprising one or more pivoted supporting arms, means for pivotally supporting said contact device on said arms, one or more stops for holding said contact device from swinging movement with the 15 arms during a portion of the movement of said arms to cause a relative angular movement of the contact device and the arms, and means to limit the pivotal movement of the device with relation to the arms in both directions.

9. A typewriting machine comprising a substantially flat platen, a series of type levers, power means for operating said levers, a series of shiftable type heads mounted on the respective levers, mechanism for shifting said heads comprising a contact device associated with each head, a transverse rock shaft, a key lever, connections for actuating the rock shaft from the key lever, one or more arms extending forwardly from said rock shaft, a contact device pivoted on said arms on a transverse axis and extending forwardly from said axis and rearwardly therefrom toward the rock shaft and means for limiting the upward and downward movement of the forward portion of the contact device during the corresponding movements of said arms to cause the contact device to swing with relation to said arms to locate the rear portion thereof in and out of operative position with relation to the contact devices on the type heads.

ELMER L. WISE.
